UNITED STATES PATENT OFFICE.

JOHN WALDHEIM, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,369,065.

Specification of Letters Patent. Patented Feb. 22, 1921.

Application filed February 21, 1917. Serial No. 150,010.

To all whom it may concern:

Be it known that I, JOHN WALDHEIM, a citizen of the United States, residing in Elizabeth, in the county of Union and State 5 of New Jersey, have invented certain new and useful Improvements in Combined Typewriting and Computing Machines, of which the following is a specification.

This invention relates to a combined type-

10 writing and computing machine of the Underwood-Hanson type, and is an improvement on applications Nos. 79,969, 87,672 and 89,015, (now Patents Nos. 1,282,823, 1,299,052 and 1,302,032).

15 The invention relates to devices for taking care automatically of the spacing or grouping of the digits in numbers that are written and computed, so that the operative will not need to think to write in the commas and 20 decimal points. In the present improvements, this is accomplished by having one or more of the tabulating stops formed with a series of tappets arranged at intervals from each other, to correspond to the space occupied by each group of digits separated normally by commas and decimal points.

25 Each of these tabulating stops has preferably two sets of tappets, and each stop is reversible on the carriage so that either set 30 of tappets can be used. One set may be used where dollars and cents are computed, and it is necessary to have two comma spaces and a decimal point space, and the other set may be used where ordinary numbers are 35 computed, and it is only necessary to have two comma spaces and no decimal point. The location of the special tabulating stop on the carriage determines when the tappets shall come into play; and their position on 40 the tappet determines at what letter-space interval they shall operate automatically the escapement mechanism of the typewriter carriage, to give a double letter-space after striking a key.

45 The computing mechanism is adjustable to make the denominational action agree with the particular spacing of the digits as typewritten. To do this, the jacks which control the denominational selections are 50 shiftable, so as to come into play at different space positions of the carriage. In this way they may be grouped together by spacers inserted between the desired groups.

Provision is made for silencing the auto-

matic control of extra space movements of 55 the carriage when the computing mechanism is thrown out of action by the non-compute key, and also when the platen is raised to upper-case position, as no digits are printed or computed when writing with upper-case 60 characters.

Other features and advantages will hereinafter appear.

Referring to the drawings,

Figure 1 is a view in elevation partly in 65 section taken from front to rear, with parts omitted to simplify the showing. In this view the denominational selector is shown in its raised position in action, and the bail which operates the escapement is also shown 70 in operative relation with respect to the spacing tabulator stop.

Fig. 2 is a detailed view in front elevation of the extra spacing or skipping mechanism, showing the same just before entering a computing zone.

Fig. 3 is a skeleton perspective view showing the tabulating spacing stop after it has passed beyond a computing zone.

Fig. 4 is a detailed view in the front elevation of the escapement mechanism showing the limiting member in a position to give but a single letter space movement of the carriage. This view shows the mechanism before any escapement action has taken 85 place.

Fig. 5 is a view of some of the parts shown in Fig. 4 with the limiting member in the same position; except that the loose dog has left the escapement wheel to give a 90 single letter space movement of the carriage on the return of the rocker carrying the fixed and loose dogs.

Fig. 6 is a view of the parts shown in Fig. 5 with the rocker in the same position 95 although the limiting member has been depressed to a position to give an extra letter space movement of the carriage.

Fig. 7 is a view similar to Fig. 2 with the special tabulating stop reversed so that but 100 two spaces are automatically controlled, the denominational selecting jacks being arranged accordingly.

Fig. 8 is a detailed perspective view of the tabulating stop which controls the automatic spacing of the carriage.

Fig. 9 is an enlarged vertical section from front to rear showing the denominational se-

lector and the space skipping mechanism in their inactive positions, and also showing how the cover plate for the selecting dogs can be raised to permit the change in the 5 position or grouping of the jacks by means of the spacers.

Fig. 10 is a detailed view of the totalizer showing the nine computing or dial wheels.

Fig. 11 is a top plan view of the jacks 10 showing them spaced to compute non-decimally to correspond to the skipping as to point only, between millions and hundreds of thousands, and between thousands and hundreds.

Fig. 12 is a diagrammatic view showing 15 the spacing of the denominational jack actions corresponding to decimal computing to give a space between millions and thousands, thousands and hundreds, and between 20 dollars and cents.

Fig. 13 is a diagrammatic front view of the parts seen in Fig. 11.

Numeral keys 20 and alphabet keys 21 depress key levers 22, rock bell cranks 23, so 25 as to swing type-bars 24 up rearwardly against the front side of a platen 25. The platen is mounted to rotate on a carriage 26, which travels on ways 27 under the propulsion of a spring barrel 28. The traveling 30 movement of the carriage is controlled step by step by an escapement mechanism 29, which includes a rack 30, pivotally mounted on the carriage 26 and engaging a pinion 31. The pinion 31 is prevented from rotating 35 by means of a pair of spring pressed pawls 32, which are pivoted on to an escapement wheel 33. The escapement wheel 33 is controlled in its intermittent movement by means of a pair of dogs, one, 34, being fixed 40 and the other, 35, being loose on a rocker 36. The rocker 36 is connected to be actuated by a universal frame 37 normally held in its forward position by a spring 38. The universal frame 37 is provided with a universal 45 arcuate bar 39, which, at the operation of any one of the alphabet or numeral keys 20, 21, is thrust rearwardly against the tension of the spring 38 by means of a heel 40 provided on each of the type-bars 24.

50 Normally, the escapement mechanism is in the position shown in Figs. 1 and 4, with the loose dog 35 in engagement with one of the teeth of the escapement wheel 33. When, however, a key is actuated, the universal frame 37 moves rearwardly forcing the loose dog 35 out of engagement with the escapement wheel 33, and before the latter can move any appreciable extent, brings the fixed dog 34 into engagement with the same 55 tooth. In the meantime, the loose dog 35 swings about its pivot under the pull of a spring 41.

For ordinary actions of the type-keys, the loose dog 35 will move a distance somewhat 60 less than a one-tooth movement of the es-

cavement wheel 33, and thus will permit a single letter-space movement of the carriage. The movement of the loose dog 35 is determined by a limiting member 42 which is pivoted at 43 and normally in the position 70 shown in Figs. 4 and 5. When the type key returns to its raised position, the escapement mechanism rocks back to its original position bringing the loose dog 35 into engagement with the next tooth of the escapement 75 wheel 33. Inasmuch as the spring barrel 28 is stronger than the spring 41, the carriage will travel one letter-space, and the wheel 33 will rotate one-tooth space rocking the loose dog 35 and tensioning the spring 41 until 80 the dog 35 comes into engagement with a stop 44 (Fig. 3) provided on the rocker 36.

In addition to having letter-space movements, the carriage 26 may have jump or tabulating movements. Briefly stated, the 85 tabulating mechanism includes tabulating keys 46, which, when depressed, rock key levers 47 to raise plunger stops 48. These plunger stops are positioned at letter-space intervals from each other, and come into the 90 path of carriage-carried tabulating stops 49. The stops 49 are adjustably mounted on a rack bar 50 carried by the carriage at letter-space intervals. In order to disconnect the carriage from the escapement mechanism 29 95 at the time of tabulating, the plunger stops 48 are each provided with a notch 51, which, when any one of the tabulating keys is actuated, rocks a universal lever 52 to draw down on a link 53, so as to rock a lever 54 100 carrying a roller 55. The roller 55 underlies the rack 30 and raises the same out of engagement with the pinion 31. When the tabulating key actuated returns to its normal position, the rack 30 reengages the pinion 31 and the carriage is once more under the control of the escapement mechanism. 105

The type-bars 24 have two sets of types 56 and 57 for writing lower and upper-case 110 characters. In order to effect a case-shift, the platen 25 is mounted in a carriage or frame 58, which, in turn, is mounted to move vertically by means of arms 59 on the carriage 26. The vertical movement of the platen frame is obtained by a shift frame 60 115 having a rail 61 engaging a roller 62 on the platen frame 58. The shift frame 60 is rocked by means of either one of two shift keys 63, which have arms 64 engaging in back of the shift frame 60. The mechanism 120 thus far described is common to an ordinary Underwood typewriter, and has been set forth briefly in order to bring out its relation to the invention.

In addition to performing typewriting actions, the numeral keys 20 effect a computing action which gives a combined typewriting and computing operation. To do this, the numeral keys 20 are provided with thrust links 65, which, when depressed, rock 125 130

shafts 66 to spread linkages 67, so as to depress index pins 68 provided on denominational bars 69. The bars 69 are provided with racks 70 at their front ends, so as to 5 drive the dial or computing wheels 71 to run up numbers corresponding to the numeral keys actuated. In the present instance, nine dial wheels are shown, Fig. 10. This enables, when computing decimally, to 10 compute millions, thousands, and hundreds of dollars and cents, and also enables the computing of as high as one hundred million without cents.

The denominational rack bars 69 are not 15 normally within the range of the setting linkages 67. To bring them individually within the range of the setting linkages so as to effect a selection, there is provided on the carriage 26 a denominational selector 20 72. The denominational selector 72 when not in the computing zone, is in a depressed position, as seen in Fig. 9. When the carriage comes to a computing zone, the denominational selector 72 engages a roller 73 25 of a zone controller 74, so as to raise the selector 72 to the position shown in Fig. 1, where a tappet 75 thereon comes into engagement with the right-hand one of a series of jacks 76. Each of the jacks 76, when 30 rocked by the denominational selector 72, depresses a thrust link 77, so as to rock a bell crank 78. The bell cranks 78 engage transposition linkages 79 which raise the rack bars 69 one by one, to bring the pins 35 68 within the range of the setting linkages 67. The transposition linkages 79 are for the purpose of inverting the order of operation so that the denominational rack bars 69 will be operated beginning at the 40 left, although the denominational selecting jacks 76 are operated beginning at the right. In order to permit a certain amount of movement of the jacks 76, the thrust links 77 are loosely fitted into sockets 80 provided 45 in the jacks and held in these sockets by springs 81.

If it should be desired not to compute at any particular time, the zone controller 74 can be thrown out of action, so that it will 50 not bring the denominational selector into action. To do this, there is provided a non-compute key 82, which, when operated, thrusts rearwardly a bar 83 which rocks a bell crank 84, Fig. 3, the upper end of 55 which engages and rocks a cam arm 85 on a shaft 86. The shaft 86 has secured thereto the zone controller 74 and when thus rocked, moves the zone controller from beneath the denominational selector 72 against the tension of a spring 87 to the Fig. 9 position.

The zone controller is also adapted to be automatically thrown out of action and thus the computing mechanism thrown out of action when writing upper-case characters.

65 For this purpose, the shift frame 60 is pro-

vided with an arm 88 which has a roller 89 engaging an arcuate cam arm 90 provided on the rock shaft 86. Thus, when the shift frame is rocked to move the platen to upper-case position, the zone controller will be 70 shifted out of action.

The relation of the typewriting to the computing mechanism has been shown so that it will be readily seen how a combined typewriting and computing action can be obtained. In order to make the typewriting of the numbers easily legible, it is desired 75 that the digits be written in groups. Means is provided for doing this automatically, so as to prevent erroneous computing and typewriting action by false operation of the machine.

In the present invention the grouping is controlled automatically by skipping the typewriter carriage an extra letter space at 80 the proper points, so that the digits will be written in the proper grouping predetermined upon. As described and claimed in the above-mentioned applications, this is controlled from the tabulating mechanism. 90 That is to say, when it is desired to have a space between digits corresponding to a punctuation space, the escapement mechanism is permitted to have an added movement, so as to space the carriage an added 95 step.

In the present case, this is done by providing a special tabulating stop, Figs. 3 and 8, which has two series of tappets 91 to give two series of different selections or 100 groupings of the digits. Whichever set of tappets is in action, they come into engagement one by one with a lug 92 provided on a bail 93 pivotally mounted at 94 on a swinging plate 95. The bail 93 is normally held 105 in its raised position by a spring 96.

When one of the tappets 91, however, comes into engagement with the lug 92, it depresses the bail so as to force down a thrust link 97. The thrust link 97 is pivotally connected at its lower end to the limiting member 42, previously described. The limiting member 42 is normally in the position shown at Figs. 3, 4 and 5, with a finger 98 in the path of a rearwardly projecting 115 pin 99 on the loose dog 35. The finger 98 projects beyond the rest of the limiting member 42, so as to stop the dog 35 at a point where it will permit only a single tooth movement of the escapement wheel 33, and thus to a single letter-space movement 120 of the carriage 26. When, however, the said stop, bearing tappets 91, depresses the limiting member 42, it removes the finger 98 from the path of the pin 99, and brings an 125 inner step 100 into the path of the dog 35. The step 100 is located at such a distance from the pivot of the member 42 and from the end of the finger 98, as to catch the dog 35 at a point where it will permit an added 130

step of movement of the escapement wheel 33, and thus of the traveling carriage 26. That is to say, that when the limiting member 42 is depressed to the position of Fig. 6, 5 it permits a two-tooth movement of the escapement wheel, and a two letter-space movement of the carriage.

To enable a plurality of selections or groupings of the digits relatively to the 10 pointing-off places by changing the position of the two letter-space movements of the carriage, there is provided an element which can be readily adjusted as to its position, and reversed to change the selections. As 15 herein illustrated, the punctuation spacing-controlling element is in the form of a reversible tabulating stop which can be set at any letter-space interval along the carriage.

The form of this stop, as shown in Figs. 20 3 and 8, consists of a body portion 101 bifurcated to engage on opposite sides of the rack 50 and having extensions or bails 102 and 103 projecting in opposite directions and at right angles to the body portion 101. The 25 extension 102 has two of the tappets 91 thereon adapted to effect two skipping movements of the typewriter carriage, such as is used for pointing off at thousands and millions in a nine-wheel totalizer. The extension 103 has three of these tappets adapted to effect three of these skipping movements, for pointing off at dollars, and thousands and millions of dollars. It will be noticed by bending the extensions 102 and 30 103 in opposite directions that when the stop is reversed in its position on the bar 50, the positions of the extensions are merely exchanged or reversed, so that by properly positioning the stop 101 along the bar 50, any given zone can have its digits grouped and spaced in either one of the two ways provided for. Since the extensions 102 and 40 103 spring from the outer margins of the stop body 101 to clear the rack teeth, and are consequently narrow, they have their ends 45 104 and 105 turned inwardly or back toward the body 101, so as to engage between the teeth of the rack bar 50, thus giving rigidity to the extensions.

50 It is desirable to use the full capacity of the group of computing wheels 71. To enable this to be done and at the same time provide that there shall be a computing wheel selected for every digit typewritten, 55 but that no wheel shall be skipped, the jacks 76 which are pivotally mounted on a rod 106 are also slidingly mounted on this rod, so as to be adjustable in different groups at letter-space intervals, as shown in Figs. 12 and 13. To separate the jacks 76 into these groups and maintain them in a given relation, there are provided a plurality of spacers 107 preferably three in number, corresponding to the maximum possible number of active tappets in any zone. The

spacers 107 are slidingly and pivotally mounted on a rod 108, and are each provided with a notched wedge 109 arranged to slip between the jacks 76 and engage the rod 106 on which the dogs are pivotally mounted. To permit a change in the position of the spacers 107, the casing for the jack actions has a removable cover plate 110, which is pivoted at 111, so as to swing from the position indicated at Fig. 1 to the dotted 70 position indicated at Fig. 9. In the latter position the spacers 107 can be raised to a dotted line position shown at Fig. 9 and shifted endwise along the rod 108 to a new position between two of the other jacks 76. 75 The two desired groupings of the jacks are shown in Figs. 12 and 13 corresponding respectively to the arrangement of tappets 91 on the extensions 103 and 102.

When the computing mechanism is 80 silenced as by moving the zone controller 74 to the position of Fig. 9, it is desirable to silence at the same time the skipping of the typewriter carriage, as it might be necessary to write in every letter-space in the 85 range of the zone normally used as a computing zone. This might occur when the non-compute key 82 has been actuated, or when typewriting with upper-case characters. As both the non-compute key 82 and 90 the case-shift mechanism act on the zone controller 74 through the intermediary of the shaft 86, this shaft may be used to also silence the space skipping mechanism. For 95 this purpose, there is secured to the shaft 86 an arm 112 provided with a cam slot 113 engaged a pin 114 on an arm 115 secured to the rocking plate 95. The cam 113 is formed so that when the shaft 86 is rocked by either the non-compute key 82 or the 100 case-shift mechanism, it will swing the plate 95 forward about its pivotal axis 116, so as to move the bail 93 forward to carry the lug 92 out of the range of the tappets 91 on the special skipping stop, as shown in Fig. 9. 105 Under these conditions, the carriage can travel without operating either the computing mechanism or the space skipping mechanism, so that any ordinary typewriting can be performed. The space skipping mechanism may be locked in its ineffective position by means of a pin 117 on the lever 83, 110 engaging in a depressed portion 118 of a slot 119.

Variations may be resorted to within the 115 scope of the invention, and portions of the improvements may be used without others.

Having thus described my invention, I claim:

1. The combination with a computing 120 mechanism, of numeral keys for operating said computing mechanism, a traveling carriage connected to effect denominational selections in said computing mechanism, a tabulating mechanism including denomina- 125

- 10 tional stops and column-stops, escapement mechanism for controlling step-by-step movements of said carriage, and a series of tappets on one of said stops connected to effect automatically extra step movements of said carriage, so as to automatically space the digits, as written by said numeral keys, into groups.
- 15 2. The combination with computing mechanism, of a carriage connected to control denominational selections of said computing mechanism, escapement mechanism for controlling step-by-step letter-space movements of the carriage, numeral keys controlling both said escapement mechanism and said computing mechanism, and an extra space or skipping controlling mechanism dominating said escapement mechanism, said skipping controlling mechanism comprising a part adapted to cause one kind of spacing and reversible to give an extra spacing at a plurality of other points of the digits written and computed.
- 20 3. The combination with computing mechanism, of a traveling carriage, denominational selecting mechanism for said computing mechanism controlled from said carriage, escapement mechanism for controlling step-by-step movements of said carriage, keys for operating both said computing mechanism and said escapement mechanism, means for selectively grouping the digits as written by said numeral keys by increasing the letter-space movements of said carriage at a plurality of points, and shiftable means for changing at will the grouping of said denominational selecting mechanism, by increasing the letter-space movements at a plurality of other points, to correspond to the grouping of the digits as written.
- 25 4. The combination with computing mechanism and a set of numeral-printing keys for computing therein, of a set of jack actions, computing wheels adapted to be selected by said actions, a traveling carriage, a denominational selector carried by said carriage into successive engagement with each of said jack actions to cause the wheels to be selected, shiftable means for varying the spacing of said jack actions as related to the denominational selector, so as to vary the letter-space at which said denominational selector operates certain of said jack actions, and means separately settable for determining at what letter-spaces said keys may be operable to print.
- 30 5. The combination with computing wheels, of driving and indexing mechanism for said computing wheels, a series of selecting jacks, linkages connecting said jacks with said driving and indexing mechanism, a traveling carriage, a denominational selector carried by said carriage into successive engagement with each of said jacks, said jacks being adjustable in the direction of travel of said denominational selector, so as to vary the interval of travel of said denominational selector between successive actions of certain of said jacks, spacers for said jacks adjustable to maintain a variable spacing of said jacks, printing keys, and means separately settable for determining at what letter-spaces said keys may be operable to print.
- 35 6. The combination with computing mechanism of denominational selecting jacks connected to said computing mechanism, a rod on which said jacks are pivotally mounted for action and slidably mounted for adjustment in groups, a second rod, and a plurality of spacers for said jacks pivotally and slidably mounted on said second rod, so as to maintain said jacks in various groupings selected.
- 40 7. The combination with computing mechanism, of denominational selecting mechanism for said computing mechanism, a carriage traveling to control said denominational selecting mechanism, keys adapted to print numeral and non-numeral characters, an escapement mechanism controlled by said keys and controlling the movements of said carriage, said carriage having a regular step-by-step movement when typewriting non-numeral characters and a variable irregular series of movements when computing and typewriting with said numeral keys, and adjusting means for said denominational selecting mechanism for grouping the elements of said denominational selecting mechanism, to correspond to the irregular traveling movements of said carriage.
- 45 8. The combination with a series of computing wheels fixed as to their relative spacing, driving mechanism for said computing wheels, typewriting mechanism having a traveling carriage variable as to its movement so as to give different groupings of the digits as typewritten, and denominational selecting mechanism controlled from said carriage and controlling the drive of said fixed computing wheels, said denominational selecting mechanism being adjustable as to its groupings to correspond with the different groupings of the digits as typewritten by said typewriting mechanism.
- 50 9. The combination with computing wheels, of driving and indexing mechanism for said computing wheels, jacks for effecting denominational selections for said driving and indexing mechanism, thrust-links extending from said jacks to said driving and indexing mechanism, said jacks being pivotally mounted for action and slidably mounted for adjustment, said links having a loose connection with said jacks to allow for a certain amount of movement therebetween, comprising sockets in said jacks into which said links extend, and springs yielding holding said links in said sockets.
- 55 60 65 70 75 80 85 90 95 100 105 110 115 120 125 130

10. In a combined typewriting and computing machine, the combination with a traveling carriage, of an escapement mechanism for said carriage, a series of computing wheels, a denomination-selector for said wheels, connections whereby said escapement mechanism may feed said carriage single or double steps, tabulating mechanism for said carriage including a rack-bar and 5 stops settable thereon, a bail forming an extension of one of said stops adapted to cause said carriage to feed a double step at a plurality of points predetermined distances from the stop, an extension of said bail 10 adapted to engage said rack-bar to steady it, and connections whereby the selector may be effective to select adjacent wheels at the successive steps fed by the carriage.
11. In a computing machine, a register 20 having dial wheels equally spaced, driving elements for said dial wheels, denominational elements for said driving elements, numeral-printing keys, a tabulating device for determining where the keys shall print, 25 said device including a rack-bar and stops settable thereon, an extension of one stop comprising a plurality of tappets adapted to successively effect a grouping of the printed numbers, and means for varying 30 the grouping of the denominational elements to conform to the grouping effected by said tappets while maintaining the grouping of the driving elements.
12. The combination with a traveling carriage and a rack thereon comprising teeth, 35 of stops settable between said teeth, a bail comprising a stop also settable between said teeth, a plurality of tappets on said bail, an extension of the bail on the free end thereof 40 adapted to enter between teeth on said rack to steady the bail, a second bail fast to said stop extending in the opposite direction from said first bail, so that by reversing said stop, the bails may have their positions 45 changed, and a second extension on said second bail adapted to enter between teeth on said rack to steady that bail, said second bail comprising a plurality of differently distributed tappets.
- 50 13. The combination with a traveling carriage and a rack thereon comprising teeth, 55 of stops settable between said teeth, a bail comprising a stop also settable between said teeth, a plurality of tappets on said bail, and an extension of the bail on the free end thereof adapted to enter between teeth on 60 said rack to steady the bail.
14. In a computing machine, a register having dial wheels equally spaced, driving elements for said dial wheels, denominational elements for said driving elements, printing numeral keys, means for effecting different groupings of the printed numbers, and means for changing the grouping of 65 said denominational elements while maintaining the grouping of said driving elements.
15. In a computing machine, a register having dial wheels equally spaced, driving elements for said dial wheels, denominational elements for said driving elements, 70 numeral-printing keys, a tabulating device for determining where the keys shall print, said device including a rack-bar and stops settable thereon, a pair of extensions on one 75 of said stops comprising two sets of differently grouped tappets, adapted to successively effect different groupings of the printed numbers, and means for varying the grouping of the denominational elements to 80 conform to the grouping effected by said tappets while maintaining the grouping of the driving elements.
16. In a combined typewriting and computing machine, the combination with a 85 traveling carriage including a denomination-selector and numeral-printing keys, of a tabulating device including a rack-bar on said carriage, a bail settable on said rack-bar comprising a plurality of tappets 90 adapted to variably group the printed numbers, and a plurality of separately settable stops also mounted on said rack-bar adapted to coöperate with said tabulating device to position the carriage.

JOHN WALDHEIM.
